STRIPING OR BANDING MACHINE

Alfred Johnson, Uniontown, Pa., and Robert H. Johnson, Morgantown, W. Va.

Application January 23, 1934, Serial No. 707,958

7 Claims. (Cl. 91—12)

The present invention relates to new and useful improvements in striping or banding machines, particularly for tumblers, but it is to be understood, of course, that a machine in accordance with the present invention may be used for ornamenting other types of receptacles, such, for example, as buckets, tubs, flower pots, etc.

An important object of the invention is to provide a striping or banding machine of the type including one or more applicator stations, together with novel means for delivering the tumblers or other receptacles to said stations and conveying said tumblers or other receptacles away from the stations upon the completion of the striping or banding operation.

Another important object of the invention is to provide, in a manner as hereinafter set forth, a machine of the character described comprising novel means for applying the stripe or band to the work.

Other objects of the invention are to provide a striping or banding machine for tumblers and other receptacles which will be comparatively simple in construction, strong, durable, highly efficient and reliable in operation, compact, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in top plan of a striping or banding machine constructed in accordance with the present invention.

Figure 2 is a view in vertical section through the machine.

Figure 3 is a horizontal sectional view, taken substantially on the line 3—3 of Figure 2.

Figure 4 is a view in vertical section, taken substantially on the line 4—4 of Figure 3.

Figure 5 is a detail view in top plan, showing the tension spring regulating means illustrated in Figure 4.

Figure 6 is a horizontal sectional view, taken substantially on the line 6—6 of Figure 2.

Figure 7 is a detail view in bottom plan of the rotary table.

Figure 8 is a detail view in vertical section, taken substantially on the line 8—8 of Figure 3.

Figure 9 is a view principally in vertical section through the rotary color pan and its supporting and driving means.

Figure 10 is a top plan view of the motor sup-

porting bracket, showing the gear housing attached therebeneath.

Figure 11 is a detail view in perspective of the scraper.

Figure 12 is a detail view in vertical section 5 through the applicator wheel, taken substantially on the line 12—12 of Figure 3.

Figure 13 is a detail view in perspective of the color regulator.

Figure 14 is a detail view in vertical section 10 through one of the mandrels, showing the same mounted on its supporting shaft.

Referring now to the drawings in detail, it will be seen that the embodiment of the invention which has been illustrated comprises a supporting 15 structure which is designated generally by the reference numeral 1, said supporting structure including a base 2 which is mounted on suitable legs 3. Mounted on the base 2 in vertically spaced relation thereto is a platform 4 which is secured in position by bolts 5 having spacing sleeves 6 20 thereon.

The platform 4 includes a centrally located, vertical bearing 7 in which a tubular shaft 8 is journaled. Fixed on the upper end portion of the tubular shaft 8 is a rotary horizontal table 9 having bearings 10 thereon in which radial shafts 11 are journaled. The outer ends of the shafts 11 carry tapered mandrels 12 having resilient work retaining fingers 13 recessed therein. 25

The reference numeral 14 designates a vertical shaft which extends rotatably through the tubular shaft 8 and through the base 2 of the supporting structure 1. Fixed on the lower end portion of the vertical shaft 14 is a worm gear 15 which is operatively connected, by gears 16, to an electric motor 17 mounted beneath the base 2. Any suitable means, such as a thrust collar 18, may be provided for supporting the vertical shaft 14 on the base 2. 30 35

Also journaled vertically in the platform 4 is a shaft 19 having a gear 20 fixed on its lower end portion. The gear 20 is driven by a gear 20' which is fixed on the shaft 14 between the platform 4 and the base 2. The tubular shaft 8 is 45 driven from the shaft 19 by a Geneva gear designated generally by the reference numeral 21 for intermittently rotating the table 9. Fixed on the inner ends of the shafts 11 are beveled gears 22 which are driven by a beveled gear 23 fixed on the upper end portion of the shaft 14. It will thus be seen that the mandrels 12 and the table 9 are driven by a common source of power, said mandrels 12 being constantly rotated, the table 9 being intermittently rotated. 50 55

Mounted on the platform 4 is an applicator station which is designated generally by the reference numeral 24. The applicator station 24 includes a supporting bracket 25 which projects from the platform 4 and beneath which is secured a gear housing 26. Depending from the housing 26 is an electric motor 27. Rotatably mounted above the bracket 25 is a color pan 28 which is fixed on a supporting shaft 29 which extends rotatably into the housing 26. A train of gears 30 in the housing 26 operatively connects the pan 28 to the motor 27 for actuation thereby. The reference numeral 31 designates a removable pan which is mounted in the pan 28. Rising from the outer end portion of the supporting bracket 25 is a post 32 upon which a scraper 33 is hingedly mounted, as at 34. As best seen in Figure 9 of the drawings, the scraper 33 is engageable in the removable color pan 31.

The applicator station 24 further includes an arm 35 which projects from the platform 4 adjacent the supporting bracket 25, said arm 35 having a longitudinal slot 36 in its outer portion which accommodates a bolt 37 (see Figure 4) which adjustably secures a standard 38 on said arm 35. Pivotaly mounted on the upper end portion of the standard 38 is a fork 39 having its stem portion formed to provide a threaded socket 40 into which a rod 41 is threaded for adjustment, said rod 41 being secured by a lock nut 42. Adjustably mounted on the rod 41 is a socketed fork 43 which is secured in position by a set screw 44. Journaled in bearings 45 between the arms of the fork 43 is an applicator wheel 46 which is operable in the color pan 31, said applicator wheel being also operatively engageable with the work as it is brought to the station 24 on the mandrels 12.

It will thus be seen that the applicator wheel 46 is mounted for swinging movement in a vertical plane. Mounted on the standard 38 is a cross arm 47 in one end of which an adjusting screw 48 is threadedly mounted and in the other end portion of which a stop screw 49 is adjustably threaded. The screws 48 and 49 are operatively engageable with the end portions of a spring 50 which is mounted on the standard 38 and which is engaged with the bight portion of the fork 39 for yieldingly supporting the applicator wheel 46. The adjusting screw 48 regulates the tension of the spring 50, while the screw 49 serves as a stop to limit the upward movement of the end portion of said spring 50 which is engaged with the fork 39. Mounted on the fork 43 is a resilient, bifurcated gauge 51 which straddles the applicator wheel 46 and which is adjusted through the medium of a screw 52 which is also mounted on said fork 43. As is believed to be apparent, by operating the screw 52, the gauge 51 may be adjusted toward or away from the periphery of the applicator wheel 46 for controlling the thickness or quantity of the coloring thereon.

For each of the mandrels 12 the table 9 has formed in its lower side a socket 53 for the reception of a spring actuated locking bolt 54 which is mounted on the platform 4. As illustrated to advantage in Figure 8 of the drawings, the bolt 54 is slidably in a cylinder 55 which rises from the platform 4. Projecting laterally from the bolt 54 is an arm 56 having journaled thereon a roller 57 for engagement by a cam 58 on the lower face of the disk 59 of the Geneva gear 21. The arm 56 is operable in a vertical

slot 60 which is provided therefor in the cylinder 55.

The reference numeral 61 designates the spring which yieldingly urges the bolt 54 toward operative position.

Briefly, the operation of the machine is as follows:

The tumblers are slipped on the mandrels 12 on one side of the applicator station 24 while the table 9 is stationary. These tumblers are then carried to the applicator station 24 where they are engaged with the yieldingly supported applicator wheel 46. When the tumblers reach the station 24, the table 9 comes to rest but the tumblers continue to spin with the mandrels 12 for transferring a band of coloring thereto from the removable color pan 31 through the medium of the applicator wheel 46, as will be readily apparent. When a tumbler reaches the station 24, the bolt 54 engages in one of the sockets 53 for positively locking the table 9 against rotation during the striping or banding operation. Substantially simultaneously with the engagement of the disk 59 again with the star wheel, the cam 58 disengages the bolt 54 from the table 9 to permit said table to be actuated the next step for carrying the tumbler which has been striped or banded away from the station 24 and for bringing the next tumbler to said station where the operation is repeated. After leaving the station 24, the tumblers may be removed by another operator. It may be well to here mention that, if desired, each machine may be provided with a plurality of the applicator stations 24.

The mounting of the applicator wheel 46 permits said wheel to be conveniently adjusted for operation on various sizes or shapes of tumblers. In Figure 2 of the drawings, the tumblers being treated are designated by the reference numeral 63. It will be noted that the applicator wheel 46 is positioned at right angles to the surface of the tumbler with which it is engaged. When the tumblers are brought into the applicator station 24, the wheel 46 is depressed slightly thereby and maintained in yielding engagement therewith by the spring 50. The scraper or agitator 33 rides in the inner pan 31 as said pan rotates and prevents settling of the pigment in the bottom thereof, as will be apparent. The removable inner pan 31 facilitates the use of different colors. When it is desired to remove or insert the inner pan 31, the scraper or agitator 33 is swung to inoperative position on its hinge 34.

While the machine herein illustrated is for use in applying a colored stripe to the tumbler or other receptacle, said machine may, by a slight alteration, be utilized for making a frosted or roughened band on the tumbler or other receptacle. This may be expeditiously accomplished by removing the color pans, etc., together with the applicator wheel 46 and substituting for said applicator wheel an abrading wheel driven by any suitable means, such as an electric motor. This abrading wheel may be operatively connected, for example, to the motor 17 or the motor 27 for actuation thereby.

It is believed that the many advantages of a striping or banding machine constructed in accordance with the present invention will be readily understood and although a preferred embodiment of the invention is as illustrated and described, it is to be understood that changes in the details of construction and in the combination and arrangement of parts may be resorted

to which will fall within the scope of the invention as claimed.

What is claimed is:—

1. A receptacle ornamenting machine of the class described comprising a supporting structure, a table rotatably mounted on the supporting structure, mandrels rotatably mounted on the table for spinning the receptacles, a shaft rotatably mounted on the supporting structure, drive means for the shaft, means operatively connecting the mandrels to the shaft for actuation thereby, means including a Geneva gear connecting the table to the shaft for intermittent actuation thereby, a spring actuated bolt mounted on the supporting structure and operatively engageable with the table for releasably locking said table against idle rotation, means operatively connecting the bolt to the Geneva gear for actuating said bolt to retracted position when power is applied to the table, and a rotary ornamenting member operatively engageable with the receptacles.

2. A receptacle ornamenting machine of the class described comprising a supporting structure including a base and a platform spaced above said base, a tubular shaft journaled vertically in the platform, a horizontal table fixed on the upper portion of the tubular shaft, a plurality of mandrels rotatably mounted on the table for spinning the receptacles, a vertical shaft extending rotatably through the tubular shaft, means for actuating the second named shaft, means operatively connecting the mandrels to the second named shaft for constant actuation thereby, a vertical shaft journaled in the platform, gears operatively connecting the third named shaft to the second named shaft for constant actuation thereby, a Geneva gear operatively connecting the first named shaft to the third named shaft for intermittent actuation thereby, a spring pressed bolt mounted on the platform and operatively engageable with the table for releasably locking said table against idle rotation, an arm projecting from the bolt, a cam on the Geneva gear engageable with the arm for actuating the bolt to retracted position, and a rotary ornamenting member operatively engageable with the receptacles.

3. A receptacle ornamenting machine of the class described comprising a supporting structure, a table rotatably mounted on the supporting structure, mandrels rotatably mounted on the table for spinning the receptacles, means for constantly spinning the mandrels, means for intermittently rotating the table, and a striping station mounted on the supporting structure and engageable successively with the receptacles when the table is stationary, said striping station including a pan for the reception of coloring material rotatably mounted on the supporting structure, means for rotating the pan, a hinged agitator operatively engageable in the pan, a standard adjustably mounted on the supporting structure, an arm pivotally mounted on the standard, said arm including a socketed fork pivotally connected to the standard, a rod adjustably threaded into the fork, another fork mounted for rotary adjustment on the rod, an applicator wheel journaled in the second named fork and operable in the pan, said applicator wheel being engageable with the receptacles on the mandrels, resilient means mounted on the standard and engaged with the first named fork for yieldingly supporting the applicator wheel, and an adjustable gauge mounted on the second named fork

for controlling the coloring matter on the applicator wheel.

4. A receptacle ornamenting machine, comprising a supporting structure, a table rotatably mounted on the supporting structure, mandrels rotatably mounted on the table for spinning the receptacle, means for constantly spinning the mandrels, means for intermittently rotating the table, and a striping station including an applicator engageable successively with the receptacles when the table is stationary, said station including a member connected with the supporting structure, and paralleling a mandrel when the frame is over the striping station, said member having a longitudinally extending slot therein, a standard having a part passing through the slot, means for holding the standard in adjusted position in the slot, an arm pivotally mounted on the standard, means for adjusting the length of the arm, the free end of the arm carrying the applicator and adjustable resilient means carried by the standard and engaging the arm for holding the applicator resiliently against a receptacle.

5. A receptacle ornamenting machine of the class described comprising a supporting structure, a table rotatably mounted on the supporting structure, mandrels rotatably mounted on the table for spinning the receptacles, means for spinning said mandrels, means for intermittently rotating the table, and a striping station mounted on the supporting structure and engageable successively with the receptacle when the table is stationary, said striping station including a pan mounted on the supporting structure for the reception of coating material, means for rotating said pan, a standard, an arm pivotally mounted on said standard, an applicator wheel pivotally mounted on said arm and operable in said pan, said applicator wheel being engageable with the receptacles on the mandrels, and resilient means mounted on the standard and engageable with said arm for yieldingly supporting the applicator wheel.

6. In a receptacle ornamenting machine of the class described including a supporting structure, a table rotatably mounted on the supporting structure, mandrels rotatably mounted on the table for spinning the receptacles, means for rotating said table, a striping station engageable successively with the receptacles when the table is stationary, said striping station including a pan for the reception of coating material, means for rotating said pan, an applicator wheel operable in said pan, said applicator wheel being engageable with the receptacles on the mandrels, and a hingedly mounted agitator adjacent said pan and extending in its lowermost position therein.

7. In a banding machine of the class described, article holding means, a post, means for adjusting the post parallel to the axis of the holding means, an arm pivoted to the post, means for adjusting the length of the arm, an applicator wheel rotatably supported by the free end of the arm, a receptacle into which the wheel extends, resilient means cooperable with said arm and said post for holding the wheel against an article, means for varying the tension of said resilient means, and means for adjusting the pressure contact of the periphery of the wheel against the article.

ALFRED JOHNSON.
ROBERT H. JOHNSON. 75
